UNITED STATES PATENT OFFICE.

THOMAS GEORGE STILES, OF ARLINGTON, NEW JERSEY, ASSIGNOR TO THE T. GEO. STILES COMPANY, OF ARLINGTON, NEW JERSEY, A CORPORATION OF NEW JERSEY.

PIPE-CARRIER.

1,253,440.

Specification of Letters Patent.

Patented Jan. 15, 1918.

Application filed March 29, 1916. Serial No. 87,461.

To all whom it may concern:

Be it known that I, THOMAS GEORGE STILES, a citizen of the United States, and a resident of Arlington, in the county of 5 Hudson and State of New Jersey, have invented certain new and useful Improvements in Pipe-Carriers, of which the following is a specification.

This invention relates to pipe-carriers for 10 supporting pipe-rods along railway tracks, etc., and the main object of the invention is to provide an improved pipe-carrier having independent units, preferably interchangeable, in which each pipe-rod is retained in 15 position by an element that is removable without disturbance of any adjacent element for retaining in place another pipe-rod, all other devices of this type with which I am familiar being so constructed that the removal 20 of any individual pipe-retainer cannot be effected without the removal of a holding device for each of the adjacent pipe-retaining elements.

Another important feature of my improved pipe-carrier is the provision of means 25 for increasing the rigidity and strength of apparatus of this type, while at the same time reducing its cost and reducing also the number of concrete piers of iron foundations 30 required to support the pipe-carriers proper. These and other advantages I secure by mounting the pipe-supporting uprights on a new type of pipe-carrier top, the new top preferably employed by me being a rail supported substantially horizontally and set on edge so as to present the smallest surface for 35 clogging with snow, ice, dirt, etc., and requiring a supporting foundation of minimum area, while of such a nature as to give 40 the maximum of strength and rigidity. This rail is preferably an angle-iron for the two-fold purpose of obtaining the maximum amount of strength and rigidity as a support for the elements carried thereby and 45 the minimum surface for proper attachment to the usual foundations of apparatus of this class. An important additional advantage resulting from the use of rail or angle-iron tops for pipe-carriers is that the number of 50 parts and the time required in the construction of new plants, the alteration of existing plants and the maintenance of both, are much less than is the case with the devices heretofore used in pipe-carriers.

55 Other objects and advantages of the in-

vention will appear in the following description and are illustrated in the accompanying drawings, in which—

Figure 1 is a side elevation of a multiple pipe-carrier illustrating my present invention and embodying an angle-iron pipe-carrier top mounted on a concrete pier of the usual type.

Fig. 2 is a plan of the same.

Fig. 3 is an end elevation of the same. 65

Fig. 4 is an end elevation, corresponding to Fig. 3, illustrating one feature of my invention in connection with pipe-supporting uprights mounted on a wood top supported on a concrete pier. 70

Fig. 5 is a side elevation of the apparatus of Fig. 4 with one of the pipe-retainers raised from its bearings as in Fig. 1.

Fig. 6 is an elevation of a modified form of the device. 75

Fig. 7 is an enlarged side elevation of a portion of one unit of the pipe-carrier, illustrating a pipe-retaining roll mounted in its supporting bearings.

Figs. 8 and 9 are end views, on the same scale, of said roll and one of the bearings. 80

Similar characters designate like parts in all the figures of the drawings.

Referring first to Figs. 1-3 inclusive, I have illustrated in these views all of the various features of the invention hereinbefore set forth, that is to say, the improved pipe-retainer removable independently of every other pipe-retainer and without disturbing any other, the rail or angle-iron top 85 for supporting the uprights that carry the pipes and their retainers, etc., and the foundations of small area (and small horizontal cross-section throughout) for supporting said top and the pipe-carrier proper mounted on it. 90

Considering first that feature of my invention which relates to the retaining of the pipe-rods in place and the removal of individual retainers without disturbance of others, 2 designates a series of pipe-supporting uprights which preferably have suitable bearings for the usual pipe-supporting rolls or sheaves, 3, represented as curved to conform substantially to the curvature of the 105 pipe-rods 4 to be carried thereby. At their upper ends the uprights 2 preferably have open-top half-bearings, such as 5, for receiving suitable pipe-retaining devices. So far as just described these elements of the 110

pipe-carrier have the general characteristics of these parts as found in pipe-carriers in general use.

In various specific respects, however, certain of these parts will be modified, as compared with the corresponding devices of the art, when adapted for the embodiment of the new features of my pipe-retainer. The half-bearings 5 in this construction are intended to receive the end portions of individual pipe-retaining elements, such as pipe-retaining rolls 6. These pipe-retainers preferably embody a main part or roll from the ends of which project elements, such as 7, constituting practically trunnions for supporting the pipe-retainers 6 in the half-bearings 5. Each of these retainers is intended to be supported in said bearings in such a manner that it can be readily removed without disturbance of either of the corresponding retainers at opposite sides thereof. While this may be accomplished in various ways the units 6-7 are here so constructed as to be not only in horizontal alignment with each other in the series but also in end-to-end abutment without overlapping. Thus not more than one-half of the length of each bearing 5 is appropriated to any one supporting element or trunnion 7 and the remaining portion of said bearing is appropriated to another of the elements 7. Suitable means are employed for maintaining the retaining units 6-7 in place in their bearings, the construction shown being one in which each unit is held in place by two cotter-pins, 8, passing through openings, 9, extending transversely into or through the side walls of the bearings 5 and also extending in this case through recesses, 10, cut in the sides of the trunnions 7. When the pipe-retainer is in place in its bearings it will be found that it will only be necessary to pass a pair of cotter-pins through the appropriate holes and recesses 9 and 10 to lock said retainer firmly in place, and that when it is desired to remove said retainer from its bearings it is merely necessary to withdraw said cotter-pins and then raise the retainer vertically as illustrated in Figs. 1 and 5.

By means of the construction just described any number of pipe-carriers constituting independent units, and preferably interchangeable units, may be assembled in a series and any one or more of the pipe-retainers removed without disturbance of any other one if it is desired for any reason to get at a pipe-rod as in renewal or repair work.

The second important feature of my invention embodied in the construction illustrated in Figs. 1-3 inclusive is, as before stated, the means for supporting the individual uprights 2 and for increasing the strength and rigidity of the tops on which

the pipe-carriers proper are mounted. The principal element of the preferred means employed for this purpose is a metallic rail disposed substantially horizontally and set on edge so as to present the minimum surface horizontally for the accumulation of snow, dirt, etc., and for clogging thereby. Usually this metallic rail will be in the form of an angle-bar of L shape, the two parts of this angle-bar being usually just wide enough to perform their functions properly without presenting surfaces of unnecessary width. This is important not only for the reason just stated but also because with an angle-bar having a comparatively narrow horizontal web a foundation correspondingly narrow may be employed. Here said foundation is of concrete, iron or other suitable material. In Figs. 1-3 inclusive 11 designates the vertical web or rail proper, to which the supporting uprights 2 are intended to be secured, and 12 designates the horizontal web extending therefrom in the angle-bar illustrated. It will be noticed that the vertical web of this angle-bar, that is the bar proper, is bored at regular intervals, as indicated at 13, this being for the purpose of passing suitable fastening devices, such as bolts, 14, through said bar and thereby securing the uprights 2 to said bar or rail, suitable tightening nuts, 15, are shown in connection with the bolts 14.

In the construction illustrated in the first three views it will be noticed that the uprights 2 have substantially vertical faces for engagement with and attachment to the corresponding vertical faces of the bar 11. This of course gives a construction in which the minimum horizontal surface is presented for the accumulation of snow, ice, dirt, etc., and consequent clogging of the parts. The preferred construction is one in which each of the uprights 2 is forked at its lower end, as indicated at 16, and straddles the bar or rail 11, so that it has a considerable extent of bearing surface at the sides of the bar in addition to that at the top edge of the bar, the construction being such that a single bolt, such as 14, is sufficient to hold each upright firmly in its proper position. There is of course a corresponding ease and simplicity in the operations of attaching said uprights to and detaching them from said bar, the amount of time required being practically the least possible for the purpose, no superfluous parts being employed and no special adjustments being required.

An important advantage resulting from the employment of a bar or rail, such as the angle-bar 11-12, is that it may be made long enough to extend crosswise of its pier or foundation (and crosswise of the tracks) considerable distances beyond the edges of its immediate support. This is due to its

great rigidity; and in turn the additional length of pipe-carrier top thus obtained permits the substantially indefinite extension of the elements of the pipe-carrier in 5 multiple lengthwise of said bar (and crosswise of the track) to accommodate additional pipe-rods as these become necessary. It will be seen from Fig. 1 that it will only be necessary to add the necessary parts and 10 fasten the upright or uprights 2 thereof in place by one or more bolts passing through the corresponding hole or holes 13 in the bar 11 to bring about the addition of another unit or units at any given point on 15 the line of way.

By referring to Fig. 3 it will be seen that the web 12 is comparatively narrow and that it therefore requires a pier or foundation having only a small supporting area. 20 Such a pier or foundation of concrete is indicated at 17, the top surface thereof being designated by 18 and being but little wider than the web 12 itself. A very great saving in the size and cost of a concrete or 25 other pier or foundation results from making the pipe-carrier tops in angle-bar form as illustrated in Fig. 3. This will be clear by comparing said construction with that shown in Fig. 4, the details of which will 30 be hereinafter described. The angle-bar 11-12 may be held to its pier or foundation in any suitable manner, as for example by threaded rods, 19, passed through holes in the web 12 and bent at their lower ends 35 and embedded in the concrete of the pier 17. Suitable nuts are illustrated at 20 for fastening the angle-bar securely to the upper side of said pier. Of course any suitable mode of connection may be employed but 40 that illustrated involves a minimum number of parts and holds the angle-bar securely in place.

In the construction illustrated in Figs. 4 and 5 I have illustrated the application of 45 the first feature of my invention hereinbefore described, viz., the retaining devices, to structures of a type heretofore generally used for supporting pipe-carriers. In these views the pipe-retainers are identical in construction with those heretofore described, as 50 are also the uprights, their supporting sheaves and the upper portions of the uprights with their half-bearings, etc., and all of these parts are designated by the same reference characters hereinbefore used. The 55 lower portions of the uprights 2 are, however, of a different type from the lower portions of the uprights previously described, they being illustrated as having spreading 60 feet, 21, extending a considerable distance crosswise of the pier on which they are mounted. These uprights are shown as secured directly to wooden tops, 22, which in turn are fastened to a concrete foundation 65 or pier, 23, by threaded bolts or rods, 24,

bent at their lower ends and embedded in the concrete in the same manner as described in connection with the parts 19, suitable nuts, 25, being shown for clamping the parts together. It will be seen that with 70 uprights of the type shown in these two views a very wide supporting surface is required as compared with the width of the corresponding surface in Fig. 3 and that there is a correspondingly larger area for 75 the accumulation of snow, ice, dirt, etc., and consequent clogging of the parts. In addition the concrete pier constituting the foundation of the apparatus is very much larger and more costly than the pier shown 80 at 17. These views illustrate, however, the point that the independent-unit feature of my improved pipe-carrier is applicable, with the pipe-retainers, cotter-pins, etc., to the old types of apparatus including the old 85 pipe-carriers, tops and foundations or piers, as well as to the new type having tops and piers or foundations of the type illustrated in Figs. 1-3 inclusive.

In Fig. 6 I have illustrated another form 90 of structure showing how a modified independent-unit pipe-retainer may be mounted on the same type of angle-bar pipe-carrier top as before described and the whole supported on an iron foundation of the kind 95 now in general use. In these views 26 illustrates the uprights, which at their lower ends are of the same construction as in Figs. 1-3 inclusive, the parts being designated by corresponding reference characters, and are connected as in said views to angle-bars in the manner before shown and described. At 100 their upper ends, however, instead of having the successive pairs of bearings for the pipe-retainers in series the elements of the 105 successive pairs are disposed in parallelism alternating with each other, and the successive retainers 27, though overlapping, are 110 separately removable from their bearings by the removal of the cotter-pins without the removal of one disturbing in any way either of the adjacent retainers.

The foundation shown in Fig. 6, at 28, is an iron one intended to support a relatively wide wooden top, such as shown in 115 Figs. 4 and 5. Here however, an angle-bar top, 11-12, is applied thereto at one side of the iron foundation in such a manner that a much smaller surface for the accumulation of snow, etc., is presented than is the 120 case when a wood top of several times the width of the web 12 is employed. This angle-bar is secured in place in substantially the same manner as the other tops, threaded bolts, 29, and nuts, 30, being shown for this 125 purpose.

What I claim is:

1. In a pipe-carrier, the combination with a foundation, of a substantially horizontal angle-bar one element of which is secured to 130

said foundation and the other of which is disposed substantially vertically, said angle-bar being secured to said foundation in such a manner that a considerable portion of it 5 extends beyond said foundation, and multiple pipe-supporting uprights secured to the vertical element of the angle-bar at different points in the length thereof.

2. In a pipe-carrier, the combination with 10 a foundation having a narrow supporting surface, of a narrow angle-bar one web of which rests upon and is approximately the width of said supporting surface and the other web of which is disposed substantially vertically, pipe-supporting uprights 15 secured to said vertical web at different points in the length thereof, and means carried by said uprights for supporting pipes and retaining them in place.

20 3. In a pipe carrier, the combination with a foundation, of a thin vertical web carried

by and extending upwardly therefrom, and pipe supporting uprights secured to said web and extending upwardly therefrom.

4. In a pipe carrier, the combination with 25 a foundation, of a thin vertical web removably secured thereto, pipe supporting uprights having forked lower ends straddling the web and means passing through the web and uprights for securing the latter in place. 30

5. In a pipe carrier, the combination with a foundation, of a thin vertical web removably secured thereto, pipe supporting uprights having downwardly extending spaced vertical ears arranged on opposite sides of 35 the web, and means passing through the web and through the ears for securing the uprights to the web.

Signed at New York in the county of New York and State of New York this 27th 40 day of March, A. D. 1916.

THOMAS GEORGE STILES.
